[57] CLAIM

The ornamental design for a chest drain vessel, as shown.

DESCRIPTION

FIG. 1 is a front perspective view of a chest drain vessel, showing our new design;

FIG. 2 is a front elevational view thereof;

FIG. 3 is a top plan view thereof;

FIG. 4 is a right side elevational view thereof;

FIG. 5 is a bottom plan view thereof;

FIG. 6 is a left side elevational view thereof;

FIG. 7 is a rear elevational view thereof;

FIG. 8 is a front perspective view of a second embodiment of the chest drain vessel;

FIG. 9 is a front perspective view of a third embodiment of the chest drain vessel;

FIG. 10 is a front perspective view of a fourth embodiment of the chest drain vessel;

FIG. 11 is a front elevational view of FIGS. 8 and 9;

FIG. 12 is a front elevational view of FIG. 10;

FIG. 13 is a top plan view of FIG. 8;

FIG. 14 is a right side elevational view of FIGS. 8, 9 and 10, the left side elevational view being identical to that shown in FIG. 6;

FIG. 15 is a bottom plan view of FIGS. 8, 9 and 10;

FIG. 16 is a rear elevational view of FIG. 8; and,

FIG. 17 is a rear elevational view of FIGS. 9 and 10. The top plan view of FIGS. 9 and 10 is identical to that shown in FIG. 3.

The broken line showing in FIGS. 10 and 12 is for illustrative purposes only and forms no part of the claimed design.
